CYLINDER PRINTING MACHINE

Kurt Kaufmann, Berlin-Waidmannslust, Germany, assignor to Automatic Druckmaschinenfabrik Dr. W. Hinniger und Söhne, Berlin, Germany

Application October 7, 1938, Serial No. 233,857
In Germany November 8, 1937

15 Claims. (Cl. 101—275)

This invention relates to cylinder printing machines, and more particularly to certain improvements in the mechanism for rotating the rotary elements of the inking apparatus in such machines.

As a rule, the inking apparatus of cylinder printing machines is operated from the reciprocating type carriage of the machine. However, it has already been proposed in single-revolution and double-revolution cylinder printing machines to operate the inking apparatus from the impression cylinder. In this case, the inking apparatus is operated so that its elements rotate at uniform velocity and permanently in a given direction, and the inkers of the apparatus are placed in active position with respect to the form only when the carriage moves in a given direction.

It is an object of the invention to provide an improved mechanism for rotating the rotary elements of the inking apparatus of cylinder printing machines of all kinds, including, for instance, stop cylinder machines in which the type carriage moves at variable velocity throughout its stroke.

To this end, in a machine of the kind described, mechanism is provided and operatively connected to the drive of the machine, for rotating the elements of the inking apparatus permanently in the same direction of rotation independently of the motion of the carriage, and in combination with this mechanism means operatively connected to the drive of the machine is arranged for regulating the rotation of the elements in conformity with the variable motion of the carriage.

By these means, the normally uniform rotation of the elements in the inking apparatus is regulated and adapted to the varying motion of the carriage.

It is another object of the invention to provide for an exclusively continuous, i. e., non-regulated, rotation of the elements when the carriage has been arrested.

To this end, manual means is provided for making and breaking the connection of the regulating means and the drive, and such means is operated when the carriage is arrested.

It is another object of the invention to provide improved inkers in the inking apparatus.

To this end, the diameter of the inkers is so determined that their perimeter substantially corresponds to the maximum printing length of the machine.

It is another object of the invention to so arrange the inkers that the same points on the

perimeter of the inkers co-incide with the same points of the form not at all, or only rarely. This effects a good inking of the form and is an important improvement as compared with the known inking apparatus in which the same points of the inkers invariably coincide with the same points of the form.

To achieve this object, the inkers are arranged to perform an incomplete number of revolutions, for instance, $5\frac{1}{4}$ revolutions, from the moment they are met by the form during the forward motion of the carriage, to the moment such meeting occurs again.

It is another object of the invention to provide improved means for moving the inkers out of their inking position, i. e., away from the form, when the carriage is arrested, irrespective of the position of the form with respect to the inkers, that is, whether the form is below the inkers, or not.

To this end, automatic means operatively connected to the manual means for making and breaking the connection of the regulating means and the drive, is provided for moving the inkers out of their inking position when the manual means is operated for breaking the connection.

By providing for the permanent rotation of the rotary elements in the inking apparatus after the carriage has been arrested, it is possible to ink and to adjust the parts of the inking apparatus while the carriage is stationary. Another advantage of the invention resides in that the carriage with the form can be reversed immediately after leaving the inkers, since in an inking apparatus according to the invention the last inker is provided with fresh ink all over its perimeter and there is ample time to supply with fresh ink the entire perimeter of the inker, or inkers.

In the accompanying drawings a stop cylinder machine to which the invention has been adapted, is illustrated more or less diagrammatically by way of example.

In the drawings
Fig. 1 is a side elevation showing a portion of the machine, to the extent required for the understanding of the invention.

Fig. 2 is a part sectional plan view taken on the line II—II in Fig. 1, showing that position of parts in which the carriage-reciprocating and the regulating means are active.

Fig. 3 is a detail sectional view of Fig. 2 showing that position in which the said means are inactive.

Fig. 4 is a section on the line IV—IV in Fig. 5.

- Fig. 4a is a detail sectional view of the inker mechanism drawn to a larger scale.
- Fig. 5 is a section on the line V—V in Fig. 4.
- Fig. 6 is an axial section of the inking cylinder 5 in the inking apparatus.
- Fig. 7 is a diagrammatic side elevation of the regulating means.
- Fig. 8 is a velocity diagram for the carriage of the stop cylinder machine illustrated.
- Fig. 9 is a velocity diagram for the carriage of a single and double-revolution cylinder machine.
- Referring now to the drawings, and first to Fig. 1, 18 is the frame of the stop cylinder machine, of usual construction, and 1 is its type carriage.
- 15 The means for reciprocating the carriage 1 comprises, as usually, a connecting rod 6, Fig. 2, on the crank pin of a driving spur gear 2. The shaft 5 of the driving spur gear is mounted to rotate in a bearing bracket 38. Rotation is imparted to the driving spur gear 2 by a pinion 4 on the main driving shaft 3 which is mounted to rotate in the frame 18. The driving spur gear 2 is secured on its subsidiary driving shaft 5. A combined fly wheel and pulley 7 is free to rotate about the main driving shaft 3 and is connected to the shaft by a coupling C, of known construction and therefore not shown in detail. When the coupling C is thrown in, as shown in Fig. 2, the pulley 7 is connected to the main driving shaft 3 and the carriage 1 is reciprocated by its reciprocating means 2 and 6. When the coupling is thrown out, as shown in Fig. 3, the carriage 1 is stationary. The pulley 7 is hollow and a clutch member 10, with clutching parts, for instance claws, is secured to the inner side of its web. The clutch member 10 may be integral with the web, if desired. A clutch sleeve 12 is splined on the shaft 3. At its outer end which is of larger diameter, it supports a clutch plate 11, with clutching parts projecting from both its sides, and at its inner end it is made with a pinion 13. A clutch disk 14 is placed on the shaft 3 within the larger end of the sleeve 12, and adapted to cooperate with the clutching parts on 45 the inner side of the clutch plate 11. The larger end of the sleeve 12 is grooved on its outer perimeter, and a pin 15 at the free end of an arm 16 engages in the groove. The arm 16 is fulcrumed on a stud 19 which is supported by a bracket 17 on the frame 18 of the machine. A manual member, or handle, 20 is seated on the stud 19 and equipped with an annular member 21 which is recessed for the reception of a sector 22 on the arm 16. The recess is somewhat wider than the sector and when the handle 20 is swung about the stud 19 in the direction of the arrow 23, there is an idle movement between the handle 20 and the arm 16, and then the arm 16 is swung in the direction of the arrow 24. A dog 25 is rigidly 60 connected to the handle 20 at its lower side for cooperation with a pin or roller 26 on a lug 27. The lug 27 is supported by a coupling rod 28 which is arranged to be shifted longitudinally on the frame 18, Figs. 3 and 4. The dog 25 and the rod 28 form part of the automatic means which is operatively connected to the manual means, or handle, 20, for moving the inkers out of their inking position, as mentioned in the introduction.
- The pinion 13 on the clutch sleeve 12 meshes 70 with a larger spur gear 29 which is free to turn on a stud shaft 30 secured in the frame 18, and the teeth of the pinion are so long that it does not move out of mesh with the spur gear 29 when the sleeve 12 is shifted by the means described.
- 75 A smaller spur gear 31 is also free to turn on the

stud shaft 30. Arranged to swing about the stud shaft 30 at opposite sides of the spur gear unit are the bosses of two plates 32 making up together a rocking frame. A pinion 33, with a double row of teeth, turns freely on a transverse 5 stay in the frame 32. One of its rows of teeth meshes with the larger spur gear 29 and the other row meshes with a pinion 34 which rotates about a stud in the frame 32 and, in turn, meshes with the smaller spur gear 31. Pivoted on the outer 10 end of the stud the pinion 34 rotates about, is one end of a coupling rod 35 whose other end is pivotally connected to a rocking arm 36. This arm is secured on a shaft 37 which is mounted to turn in the bearing bracket 38.

As described, the pinion 33 is in permanent mesh with the larger spur gear 29, and the pinion 34 is in permanent mesh with the smaller spur gear 31. A pinion 42, Fig. 6, is rotated from the smaller pinion 31 through a train of gears 39, 40, 41, 41, of usual construction. The pinion 42 is free to turn on the boss of a spur gear 43, and this boss is free to turn on the fixed shaft 44 of an inking cylinder 45 in the inking apparatus A. The spur gear 43 is rotated by a spur gear 46 secured on the shaft 142 of the two spur gears 41 and 41. The pinion 42 drives the inking cylinder 45 by a pin 47 making a sliding fit in a hole in the end wall of the inking cylinder. Through a train of gears which will not be described in detail, as it is of usual construction, the rotation of the spur gear 43 is transmitted to a spur gear 48 which is free to rotate on the shaft 49 of a ductor cylinder 50, Figs. 1, 4, and 5. The ductor cylinder is secured on its shaft 49. A ratchet wheel 51 is keyed on the shaft 49, and a pawl 52 pivoted on the spur gear 48 engages in the ratchet wheel under the action of a spring, not shown.

Through the said train of gears, the ductor cylinder 50 is permanently rotated in the direction of the arrow 53, Fig. 4. A vibrator 54 is arranged to cooperate with the ductor cylinder 50, and supported at the upper end of a bellcrank 58 fulcrumed on the frame at 55. A spring 56 tends 45 to hold the vibrator 54 against the ductor cylinder 50.

Forming part of the inking apparatus are distributing rollers 57. Two pairs of such rollers have been shown but it is understood that any 50 number may be provided, for transferring ink to the inking cylinder 45. Two inker rollers 58 are in contact with the inking cylinder 45. The diameter of the inkers 58 is so determined, that their perimeter, as mentioned, is substantially equal to 55 the maximum printing length of the machine. More than two inkers might obviously be provided but two are normally sufficient. Each inker 58 is mounted adjustably for rotation in the free end of an arm 59. The arms are mounted to 60 turn, scissors fashion, about the fixed shaft 44 of the inking cylinder 45, and have extensions 60 beyond the shaft. Two pins 61 are arranged for cooperation with the two extensions 60 of the arms 59, and are supported by an arm 62. The 65 boss 62a of the arm 62 is mounted to swing about a rivet 62b in a wall of the frame 18, and the arm 62 is swung by a link 63 which is pivotally connected to the shorter arm 64 of a lever which is pivoted on the frame of the machine at 66. The 70 pins 61 are not in direct engagement with the extensions 60 but bear against buffer plates 67 which are supported on the inking cylinder shaft 44, and can be adjusted with respect to the extensions 60 by screws 68. The buffer plates serve 75

for adjusting the inkers 58 in their inking or active position with respect to the form on the carriage 1. By bearing against the pins 81, the plates 61 cause an always equal swinging of the inkers 58 away from the form without slack while on the other hand the plates, by means of the adjusting screws 68, permit of the arms 59 moving nearer together to a greater or lesser extent, according to variation in the diameter of the inkers 58 due to wear. A spring 69 attached to the arms 59 tends to pull the inkers 58 together and into their inking position, Fig. 1, in which they ink the form on the carriage 1 advancing in the direction of the arrow 70.

The rocking arm 36 which, as will be remembered, is connected to the rocking frame 32 by the coupling rod 35, is controlled by an arm 11 on the inner end of its shaft 37 with a pin 12 at its free end engaging in a cam groove 73 in the inner face of the driving spur gear 2. The groove is partly concentric to the axis of the subsidiary shaft 5, and partly eccentric, and is of such configuration that rotation of the spur gear 2 in the direction of the arrow 76 causes the arms 11 and 36 to oscillate in the direction of the double arrow 74, Fig. 1, which, through the medium of the coupling rod 35, causes the rocking frame 32 to perform a similar oscillation about the stud shaft 30, and the pinions 33 and 34 in the rocking frame 32 to roll to and fro on the respective spur gears 29 and 31, resulting in the operation which will be described below.

The rocking frame 32, with its pinions 33 and 34 and the parts connected thereto, as shown separately in Fig. 7, make up the regulating means referred to, by which the otherwise uniform rotation imparted to the rotary elements of the inking apparatus A by the train of gears connected to the spur gears 29 and 31 is adapted to the varying motion of the carriage 1.

A cam plate 75 is secured on that end of the subsidiary shaft 5 which is opposite the driving spur gear 2, Figs. 1, 2, and 4, and obviously the cam plate 75 rotates with the spur gear 2 in the direction of the arrow 76. An arm 78, as best seen in Fig. 4, is fulcrumed on the frame 18 at 77, and equipped with a roller 79 for cooperation with the cam plate 75. The rod 28 which supports the roller 79 for cooperation with the dog 23 on the handle 20, is connected to the arm 78 with its front end, and a spring 80 engaging the arm 78 at its upper end holds the roller 79 against the edge of the cam plate 75.

The rear end of the rod 28 is pivotally connected to one arm of a bellcrank 81 fulcrumed on the frame of the machine, and a vertically reciprocating slide 82 is pivotally connected to the other arm. A plate 83 with a cam groove 84 is secured to the slide 82, and the longer arm 64 of the lever to whose shorter arm 64 the link 63 is connected, engages in the groove with a pin 85. By these means, the vertical reciprocation of the slide 82 causes horizontal reciprocation of the link 63 in its longitudinal direction, and this, as will be explained below, has for its consequence a lowering or raising of the inkers 58, as will be described.

A dog 86 is secured to the slide 82 and, in the position illustrated in Fig. 1, engages below a pin 87 on the bellcrank 88 which supports the vibrator 54. The vibrator is now removed from the ductor cylinder 59 against the action of the spring 56 and held against the first distributing roller 57. A handle 105 is provided on that arm 75 of the bellcrank 88 which is equipped with the

pin 87. A roller 89 on the bellcrank 88 cooperates with a sector-shaped cam 90 which is free to turn on the shaft 49 of the ductor cylinder 59 and is equipped with a spring catch 91 for holding the cam 90 in various positions with respect to a toothed sector 92 which is integral with an arm 93 and is also free to turn on the shaft 49. The upper end of the slide 82 is connected to the free end of the arm 93.

The connection between the ductor cylinder 59 and the spur gear 48 is broken by throwing out the pawl 52 from the ratchet wheel 51 which is rigidly connected to the ductor roller 50. The means for effecting this is illustrated in Fig. 5. A handle, or hand wheel, 94 is mounted to slide 15 on an extension of the shaft 49 with a sleeve. The sleeve is slotted and a pin on the shaft 49 engages in the slot so that the hand wheel 94 rotates with the shaft 49. A spring inserted in the sleeve of the hand wheel and abutted against the end of the shaft 49 holds the hand wheel 94 in the inactive position shown in Fig. 5. The inner end of the sleeve is tapered at 95 and this tapered end, upon the hand wheel 94 being pushed inwardly in the direction of the arrow 96, strikes a pin 97 on the pawl 52 and disengages it from the ratchet wheel 51.

The inking cylinder 45 is to be shifted on its shaft 44 while being rotated at uniform velocity by the pinion 42 and the pin 41. For this purpose, the means illustrated in Fig. 6 is provided. An annular cam plate 98 is secured on the boss of the spur gear 43, and an endless groove 99 is arranged in the perimeter of the cam plate at an angle to the axis of the shaft 44. A pin 100 in the end plate of the inking cylinder 45 engages in the groove 99. Since the velocities of the pinion 42 and the spur gear 43, and consequently of the cam plate 98 and the inking cylinder 45, are different, the inking cylinder 45 is shifted along the shaft 44 by the groove 99 while rotating. The distributing rollers 57 are shifted by the inking cylinder in manner per se known.

The operation of the machine is as follows: Assume that the carriage 1 is in the position 45 illustrated in Fig. 1 in which it begins to advance on its forward stroke in the direction of the arrow 70 for inking the form. The inkers 58 then assume the positions illustrated in Fig. 1 and rotate in the direction of the arrows, so that they 50 will ink the form as it moves past them in the direction 70. In this position of the parts, the vibrator 54 is in contact with the first distributing roller 57, as also shown in Fig. 1 and the slide 82 has been elevated into its topmost position by 55 the eccentric portion of the cam plate 75.

If in this position of the parts the manual means, or handle, 20 is in its outer final position in which it connects the clutch plate 11 to the clutch disk 14 which is secured on the main 60 driving shaft 3, as shown in Fig. 2, and when the motor 8 is started to rotate the main driving shaft 3 clockwise, as indicated by the arrow in Fig. 1, through the pulley 1 and the coupling C, the carriage 1 is started in the direction of the arrow 65 70 by the carriage-reciprocating means 2, 6, and at the same time, through the mechanism 20, 81, . . . 41 the inking cylinder 45 is rotated clockwise, as indicated by the arrow, and the inkers 58 are rotated anti-clockwise by the cylinder. The 70 form is now inked by the inkers 58. Since in a stop cylinder printing machine, as illustrated, the carriage 1 does not move uniformly but according to the sinus curve 104 in Fig. 8, a similar variable motion is imparted to the rotary members 75

- of the inking apparatus A, in strict conformity with the motion of the carriage 1. This is effected by the correspondingly shaped cam groove 73 in the driving spur gear 2 while the spur gear 5 rotates anti-clockwise in the direction 76. The cam groove 73 oscillates the rocking arm 36 whose oscillation is transmitted to the rocking frame 32 by the coupling rod 35, so that the rocking frame 32 also oscillates about the stud shaft 30.
- 10 When the rod 35 moves to the left in the direction of the arrow 102 in Fig. 1, the rocking frame 32, with the pinions 33 and 34, moves in the same direction and thereby the pinion 33 is rotated at a higher speed than that at which it is 15 driven by the larger spur gear 29 which is rotated at constant speed by the pinion 13 on the clutch sleeve 12. This acceleration is transmitted to the smaller spur gear 31 through the pinion 34, and finally to the rotary elements of the inking apparatus A. When the rod 35 is moved against the arrow 102 by the cam groove 73, obviously a corresponding deceleration of the inking apparatus A occurs, and while the concentric semi-circular portion of the groove moves past the roller 72, 20 the rocking arm 36 and the rocking frame 32 are not influenced, and the inking apparatus is driven uniformly. This uniform motion is imparted to the inking apparatus A from the moment the form has moved beyond the inkers 58 in the 25 direction of the arrow 70, and throughout the return of the carriage against the arrow 70, Fig. 4, since during this period the inkers 58 are clear of the form. In this manner, the velocity curve 30 103 in Fig. 8 is easily produced.
- 35 The configuration of the cam plate 75 is such that in rotating in the direction of the arrow 16 from the position in Fig. 1 it shifts the rod 28 to the right in the direction of the arrow 104 in Fig. 1 against the spring 80. This causes the slide 40 82 to descend and its dog 86 to release the pin 87 of the bellcrank 88. The spring 56 is now free to force the vibrator 54 against the ductor cylinder 50 and to receive fresh ink. This position of parts is illustrated in Fig. 4. This is the lowermost position of the slide 82 which ceases to descend when the form with the carriage 1 has left the inking apparatus A and is in the position according to Fig. 4. At the same time, the descending cam plate 83 swings the double-armed 45 50 lever 64, 65 from the position in Fig. 1 into that in Fig. 4 in which the link 63 has moved to the right and the arm 62 assumes the inclined position in Fig. 4. Its pins 62 spread apart the inker arms 59 against their spring 69, lifting the inkers 55 58 beyond the upper surface of the form. In this position, the inkers 58 remain until the form has returned into its initial position, Fig. 1, and no inking occurs during the return of the carriage 1.
- 60 The cam plate 75 when turning from the position in Fig. 4 in the direction 76 allows the spring 80 to gradually elevate the slide 82 until the concentric portion of the cam plate engages the roller 79. The consequence is that before the 65 roller 79 is engaged by the concentric portion, the sector cam 90 has been turned in the direction of the arrow in Fig. 4 by the arm 93 of the toothed sector 92, that the cam engages the roller 89 on the bellcrank 88 and removes the vibrator 54 from the ductor roller 50 before the ascending dog 86 on the slide 82 throws over the bellcrank. However, the vibrator 54 is not yet in contact with the first distributing roller 57. This 70 contact is effected only after the slide has completed its ascending motion, the dog 86 engaging

the bellcrank 88 and throwing it over to place the vibrator 54 against the first distributing roller 57.

The moment at which the sector 90 separates the vibrator 54 from the ductor roller 50 is varied by adjusting the cam sector 90 with respect to the arm 93 through the toothed sector 92 and the spring catch 91. By these means, the width of the strip of ink taken from the ductor cylinder 50 in the direction of its perimeter is varied as desired.

When it is desired to arrest the carriage 1, the coupling C between the pulley 7 and the main driving shaft 3 is thrown out in the usual manner. When the handle 20 is now turned in the direction of the arrow 23 in Fig. 2, and into the 15 position illustrated in Fig. 3, and the clearance between the parts 21 and 22 has become exhausted, the arm 16 moves the clutch plate 11 into engagement with the clutch member 10 on the pulley 7 and so the pinion 13 on the sleeve 12 20 is rotated, notwithstanding the main driving shaft being arrested. The pinion operates the inking apparatus A through the means described notwithstanding the stopping of the carriage 1, and this is useful for applying ink of a different 25 color, or for regulating the supply of the ink while the rotary elements of the inking apparatus rotate at uniform velocity. When the handle 20 is moved into the position illustrated in Fig. 3 from that in Fig. 2, its dog 25, through the pin or 30 roller 26 on the bracket 27, shifts the rod 28 in the direction of the arrow 104, Fig. 1, and into the position illustrated in Fig. 4, independently of the cam plate 75 which may assume any position at this moment, and by these means, as described, 35 the inkers 58 are elevated by the turning of the handle 20 so that they will not ink the form if the carriage stops below the inkers.

Upon the continued operation of the inking apparatus A the ductor cylinder 50 is rotated from 40 spur gear 48 through pawl 52, so that the vibrator 54 can take any quantity of ink from the ductor cylinder 50 and transfer it to the first distributing roller 57, by moving the vibrator 54 away from the ductor roller 50, and against 45 the distributing roller 57, by the handle 105 of the bellcrank 88.

Since the ductor cylinder 50 continues its rotation after the carriage 1 has been arrested, the doctor blade 108 can also be adjusted as desired. 50

If it is desired to arrest the ductor cylinder 50 without interfering with the operation of the other elements in the inking apparatus A, the hand wheel 34 is pushed in the direction of the arrow 96, Fig. 5, whereby the ductor cylinder 55 is disconnected from the spur gear 48, as described, and can now be turned as desired by the hand wheel 94.

When the handle 20 is returned into the position in Fig. 2 from that in Fig. 3 while the coupling C is still thrown out, and the main driving shaft 3 is not rotated, the drive 29 etc. of the inking apparatus A is also interrupted. When the coupling C is thrown in, and the pulley 7 is connected to the main driving shaft 3, the machine 65 is operated again in the manner described, including the regulating means 73 etc., by which the inking apparatus A is driven in conformity with the movement of the carriage 1, as described. As the regulating means upon the stopping of the 70 carriage remains standing exactly in that position which corresponds to the position of the carriage 1, the drive of the inking apparatus A is operated exactly in conformity with the motion of the carriage 1 when the carriage is restarted. 75

If the invention is adapted not to a stop cylinder machine, as illustrated but to a single or double-revolution cylinder machine, by way of example, whose velocity curve is illustrated at 5 106 in Fig. 9, in dotted lines, the regulating means 73 etc. is preferably so constructed that the full-lines curve 107 is produced, allowing the carriage 1, with the form, to be reversed at the front end at a short distance from the last inker 58.

10 It will appear from the foregoing description that the drive for the inking apparatus according to the invention has the advantage that the carriage is not required to drive the inking apparatus, i. e., the rotation of the inking elements is not decelerated until the elements stop, and then the elements are accelerated again. The consequence is that a printing machine according to the invention has a much lower power demand than one equipped with the known inking 15 apparatus and can be operated at a much faster rate, the more so as the carriage does not drive the inking apparatus. The rotation of the elements in the inking apparatus in the same direction is favorable with respect to the distributing 20 rollers 57 since they are not subjected to alternating but to unidirectional stress.

I claim:

1. In a cylinder printing machine, a type carriage, a form on the carriage, a drive, means operatively connected to the drive for reciprocating the carriage, an apparatus for inking the form including inkers and other rotary elements, means for placing the inkers in inking position with respect to the form only when the carriage moves in a given direction, mechanism operatively connected to the drive for rotating the elements of the inking apparatus permanently in the same direction independently of the motion of the carriage, and means operatively connected to the drive for regulating the rotation of the elements in conformity with the variable motion of the carriage.

2. In a cylinder printing machine, a type carriage, a form on the carriage, a drive, means for reciprocating the carriage, means for connecting the carriage-reciprocating means to, and disconnecting it from, the drive, an apparatus for inking the form including inkers and other rotary elements, means for placing the inkers in inking position with respect to the form only when the carriage moves in a given direction, mechanism operatively connected to the drive for rotating the elements in the inking apparatus permanently in the same direction independently of the carriage-reciprocating means, and regulating means operatively connected to the carriage-reciprocating means for regulating the rotation of the elements in conformity with the variable motion of the carriage.

60 3. In a cylinder printing machine, a type carriage, a form on the carriage, a drive, means operatively connected to the drive for reciprocating the carriage, an apparatus for inking the form including inkers whose perimeter substantially corresponds to the maximum printing length of the machine, and other rotary elements, means for placing the inkers in inking position with respect to the form only when the carriage moves in a given direction, mechanism operatively connected to the drive for rotating the elements of the inking apparatus permanently in the same direction independently of the motion of the carriage, and means operatively connected to the drive for regulating the rotation of the

elements in conformity with the variable motion of the carriage.

4. In a cylinder printing machine, a type carriage, a form on the carriage, a drive, means operatively connected to the drive for reciprocating the carriage, an apparatus for inking the form and including inkers arranged to perform an incomplete number of revolutions in the intervals between their meetings with the form during the advance of the carriage, and other rotary elements, means for placing the inkers in inking position with respect to the form only when the carriage moves in a given direction, mechanism operatively connected to the drive for rotating the elements of the inking apparatus permanently in the same direction independently of the motion of the carriage, and means operatively connected to the drive for regulating the rotation of the elements in conformity with the variable motion of the carriage.

5. In a cylinder printing machine, a type carriage, a form on the carriage, a drive, means for reciprocating the carriage, means for connecting the carriage-reciprocating means to, and disconnecting it from, the drive, an apparatus for inking the form including inkers, a ductor roller, a vibrator, a distributing roller, and other rotary elements, means for placing the inkers in inking position with respect to the form only when the carriage moves in a given direction, mechanism operatively connected to the drive for rotating the elements in the inking apparatus permanently in the same direction independently of the carriage-reciprocating means, means for connecting the mechanism to, and disconnecting it from, the drive, means for removing the inkers from the form, and the vibrator from the distributing roller, when the carriage has been disconnected from, and the mechanism has been connected to, the drive, and regulating means operatively connected to the carriage-reciprocating means for regulating the rotation of the elements in conformity with the variable motion of the carriage.

6. In a cylinder printing machine, a type carriage, a form on the carriage, a drive, means operatively connected to the drive for reciprocating the carriage, an apparatus for inking the form, a pair of arms connected scissors-fashion on the apparatus, an inker at the free end of each arm, other rotary elements in the inking apparatus, means for spreading apart the inker-supporting arms, a cam plate operatively connected to the drive for controlling the spreading means, mechanism operatively connected to the drive for rotating the elements of the inking apparatus permanently in the same direction independently of the motion of the carriage, and means operatively connected to the drive for regulating the rotation of the elements in conformity with the variable motion of the carriage.

7. In a cylinder printing machine, a type carriage, a form on the carriage, a drive, means operatively connected to the drive for reciprocating the carriage, an apparatus for inking the form, a shaft on the apparatus, a pair of arms arranged scissors-fashion on the shaft, an inker at the free end of each arm, an extension on the other end of each arm, an adjustable buffer plate on each extension, an arm, pins on the arm for cooperation with the buffer plates, means operatively connected to the arm for spreading apart the inker-supporting arms through the arm and the buffer plates, other rotary elements in the inking apparatus, mechanism operatively connected to the drive for rotating the elements of the inking ap-

paratus permanently in the same direction independently of the motion of the carriage, and means operatively connected to the drive for regulating the rotation of the elements in conformity with the variable motion of the carriage.

5 8. In a cylinder printing machine, a type carriage, a form on the carriage, a drive, means operatively connected to the drive for reciprocating the carriage, an apparatus for inking the form

- 10 including inkers and other rotary elements, means for placing the inkers in inking position with respect to the form only when the carriage moves in a given direction, mechanism operatively connected to the drive for rotating the elements 15 of the inking apparatus permanently in the same direction independently of the motion of the carriage, a pair of spur gears forming part of the mechanism, a rocking frame fulcrumed on the frame of the machine, a pinion on the rocking 20 frame which meshes with one of the spur gears, another pinion, also on the rocking frame, which meshes with the first-mentioned pinion and the other spur gear, and a rotary member operatively connected to the drive and defining a cam groove, 25 for operating the rocking frame; for regulating the rotation of the elements in conformity with the variable motion of the carriage.

9. In a cylinder printing machine, a type carriage, a form on the carriage, a main driving shaft, a driving member mounted to rotate freely 30 on the shaft, means operatively connected to the driving shaft for reciprocating the carriage, an apparatus for inking the form including inkers and other rotary elements, means for placing the inkers in inking position with respect to the form only when the carriage moves in a given direction, a clutch sleeve splined on the shaft, mechanism permanently connected to the sleeve for rotating the elements of the inking apparatus 35 permanently in the same direction independently of the motion of the carriage, clutching parts on the driving member and on the shaft, a clutch plate on the sleeve, clutching parts on the plate for cooperation with the first-mentioned clutching part, manual means for alternately connecting 40 the clutch plate to the main driving shaft and to the driving member, means operatively connected to the manual means for operating the inker-placing means, and moving the inkers off the form, in that position of the manual means 45 which corresponds to the connection of the clutch plate and the main driving shaft, and means operatively connected to the drive for regulating the rotation of the elements in the inking apparatus in conformity with the variable motion of the carriage.

- 50 10. In a cylinder printing machine, a type carriage, a form on the carriage, a drive, means operatively connected to the drive for reciprocating the carriage, an apparatus for inking the form including inkers, a ductor cylinder, distributing rollers, a vibrator, and other rotary elements: means for placing the inkers in inking position with respect to the form only when the carriage 55 moves in a given direction, mechanism for rotating the ductor cylinder and the other elements of the inking apparatus permanently in the same direction independently of the motion of the carriage, means for holding the vibrator against the first distributing roller during the inking of the form, the size of the distributing rollers being so determined with respect to the size of other rotary elements, that the form has moved clear 60 of the inkers before they are supplied with fresh ink, and means operatively connected to the

drive for regulating the rotation of the elements in conformity with the variable motion of the carriage.

11. In a cylinder printing machine, a type carriage, a form on the carriage, a drive, means for reciprocating the carriage, means for connecting the carriage-reciprocating means to, and disconnecting it from, the drive, an apparatus for inking the form including inkers, a ductor cylinder and other rotary elements, means for placing the inkers in inking position with respect to the form only when the carriage moves in a given direction, mechanism operatively connected to the drive for rotating the ductor cylinder and the other elements of the inking apparatus permanently in the same direction independently of the carriage-reciprocating means, means for arresting the ductor cylinder when the carriage has been arrested, manual means for rotating the ductor cylinder, and regulating means operatively connected to the carriage-reciprocating means for regulating the rotation of the elements in conformity with the variable motion of the carriage.

12. In a cylinder printing machine, a type carriage, a form on the carriage, a drive, means for reciprocating the carriage, means for connecting the carriage-reciprocating means to, and disconnecting it from, the drive, an apparatus for inking the form including inkers, a shaft, a ductor cylinder on the shaft, and other rotary elements, means for placing the inkers in inking position with respect to the form only when the carriage moves in a given direction, mechanism operatively connected to the drive for rotating the ductor cylinder and the other elements of the inking apparatus permanently in the same direction independently of the carriage reciprocating means, a spur gear mounted to rotate on the shaft of the ductor cylinder and forming part of the mechanism, a pawl fulcrumed on the spur gear, a ratchet wheel on the shaft arranged to be engaged by the pawl, a hand wheel splined on the shaft for rotating the ductor cylinder manually, a tapered portion on the hand wheel for disconnecting the pawl from the ratchet wheel, and regulating means operatively connected to the carriage-reciprocating means for regulating the rotation of the elements in conformity with the variable motion of the carriage.

13. In a cylinder printing machine, a type carriage, a form on the carriage, a drive, means operatively connected to the drive for reciprocating the carriage, an apparatus for inking the form including inkers, a ductor cylinder, distributing rollers, a vibrator, and other rotary elements: means for placing the inkers in inking position with respect to the form only when the carriage moves in a given direction, mechanism operatively connected to the drive for rotating the ductor cylinder and the other elements of the inking apparatus permanently in the same direction independently of the motion of the carriage, means for holding the vibrator against the first distributing roller during the inking of the form, means including a cam mounted to swing about the axis of the ductor cylinder, an arm for swinging the sector, and a device for varying the relative position of the arm and the sector, for moving the vibrator away from the ductor cylinder preparatory to its being forced against the first distributing roller, and means operatively connected to the drive for regulating the rotation of the elements in conformity with the variable motion of the carriage.

14. In a cylinder printing machine, a type carriage, a form on the carriage, a drive, means operatively connected to the drive for reciprocating the carriage, an apparatus for inking the form including inkers, a ductor cylinder, a vibrator, and other rotary elements: means for placing the inkers in inking position with respect to the form only when the carriage moves in a given direction, means for controlling the vibrator and the inkers, a cam plate operatively connected to the drive, and a slide operatively connected to the cam plate for operating the controls, mechanism operatively connected to the drive for rotating the elements of the inking apparatus permanently in the same direction independently of the motion of the carriage, and means operatively connected to the drive for regulating the rotation of the elements in conformity with the variable motion of the carriage.
15. In a cylinder printing machine, a type carriage, a form on the carriage, a drive, means

operatively connected to the drive for reciprocating the carriage, an apparatus for inking the form including inkers, a shaft, an inking cylinder mounted to slide on, and to rotate about, the shaft, and other rotary elements, means for placing the inkers in inking position with respect to the form only when the carriage moves in a given direction, mechanism operatively connected to the drive for rotating the elements of the inking apparatus permanently in the same direction 10 independently of the motion of the carriage, members forming part of the mechanism and arranged to rotate at different velocities, means on one of the members for rotating the inking cylinder, and a camming part on the other member for shifting the inking cylinder axially, and means operatively connected to the drive for regulating the rotation of the elements in conformity with the variable motion of the carriage. 15
